(57) **CLAIM**

The ornamental design for a gaming platform, as shown and described.

DESCRIPTION

FIG. 1 is a front perspective view of a gaming platform showing my new design in accordance with an embodiment; FIG. 2 is a rear perspective view thereof; FIG. 3 is a front elevational view thereof; FIG. 4 is a rear elevational view thereof; FIG. 5 is a side elevational view thereof; FIG. 6 is a top plan view thereof; FIG. 7 is a bottom plan view thereof; FIG. 8 is an exploded front perspective view thereof; FIG. 9 is a front perspective view thereof, with the board rotated 90° on its base; FIG. 10 is a rear perspective view thereof; FIG. 11 is a front elevational view thereof; FIG. 12 is a rear elevational view thereof; FIG. 13 is a side elevational view thereof; FIG. 14 is a top plan view thereof; FIG. 15 is a bottom plan view thereof; and, FIG. 16 is an exploded front perspective view thereof. The broken lines showing puzzle pieces in FIGS. 1, 3, 5, 6, 8, 9, 11, 13, 14, and 16 are included to show puzzle pieces on the gaming platform, but the puzzle pieces form no part of the claimed design.
